I. B. WELLINGTON

APPARATUS FOR SAND BLAST CARVING

Filed April 1, 1925

UNITED STATES PATENT OFFICE.

IRVING B. WELLINGTON, OF LOS ANGELES, CALIFORNIA.

APPARATUS FOR SAND-BLAST CARVING.

Application filed April 1, 1925. Serial No. 19,946.

To all whom it may concern:

Be it known that I, IRVING B. WELLINGTON, a citizen of the United States, and a resident of Los Angeles, in the county of 5 Los Angeles, State of California, have invented certain new and useful Improvements in Apparatus for Sand-Blast Carving, of which the following is a specification.

10 My invention relates to the art of carving relatively soft materials such as wood by the use of sand blasts, and it is a purpose of my invention to provide an apparatus by which the carving of wood and like is economically facilitated and without requiring the employment of skilled workmanship as is incident to the methods and apparatus now in use.

15 It is also a purpose of my invention to 20 provide an apparatus of the above described character having embodied therein pattern members constructed so as to be immune from the attack of the sand blast, and means capable of being readily assembled 25 and disassembled for securing the pattern members in fixed positions on the work to be carved, and upon the completion of the carving of one piece of work they can be removed and applied to another piece of 30 work without disturbing their positions one with relation to other.

I will describe only one form of apparatus for sand-blast carving embodying my invention and will then point out the novel 35 features thereof in claims.

In the accompanying drawings,

Figure 1 is a fragmentary perspective view of the different elements comprised in one form of apparatus embodying my invention, the elements being disassembled but in their proper respective positions for assembling and with the pattern removed from a carved piece of work.

Figure 2 is a fragmentary plan view of the locking templet embodied in the apparatus, the templet being in locking position and one of the locking studs in section.

Figure 3 is a vertical sectional view taken on the line 3—3 of Figure 1 and showing the locking and positioning templets associated with the pattern and the three elements in the act of being applied to a piece of work.

Figure 4 is a view similar to Figure 3 with the templets in the act of being removed

from the pattern and the latter in applied position to the work.

Figure 5 is a view similar to that shown in Figure 4 showing the pattern in applied position to the work and a blasting instrument in operative relation to the pattern and work.

Similar reference characters refer to similar parts in each of the several views.

Referring specifically to the drawings, my invention in its present embodiment comprises a pattern designated generally P and made up of a plurality of elements of any desired design. In the present instance, I have shown a body element p, and two letter elements p', p² the latter being positioned within the body element to co-operate therewith in forming a design for a sign. The several elements constituting the pattern are constructed of a relatively hard lamination 15 preferably formed of metal, and a yieldable or compressible lamination 16 preferably formed of rubber. Each element is provided with a plurality of pins 17 which extend and are fixed in the element so that their pointed ends project from the lower side of the element and function to position the pattern element upon a piece of work. Those portions of the pins projecting above the element serve as a means for holding the pattern element in fixed relation to the other elements when associated with a positioning templet T.

The templet T as shown in Figure 1 is in the form of a plate of suitable material 90 preferably metal and is provided at suitable points with opening 18 in which the pins 17 are adapted to be received as clearly illustrated in Figure 3. This templet is also formed with larger openings 19 which are 95 adapted to receive attaching studs 20 fixed to and upstanding from the pattern elements. These attaching studs are formed with tapered free ends to facilitate their insertion into the openings 19 and the length 100 of the studs is such that they project from the upper side of the templet for engagement with a locking templet T'. As shown in Figure 1 the locking templet T' is in the form of a plate provided with openings 21 to receive the studs and slots 22 communicating with the openings and permitting a movement of the templet on the studs so as to effect a locking engagement 105 between the two. The studs 20 are formed

with recesses 20^a which permit of the studs moving into the slots 22 and in a manner to lock the templet to the studs. The templet T' is also formed with relatively 5 large slots 23 to accommodate screws 24, the screws having threaded engagement with openings 25 in the positioning templet and thereby serving to secure the locking templet to the positioning templet by allowing 10 sufficient movement of the locking templet to permit the studs 20 to move into or out of the slots 22.

In practice, the several pattern elements p, p', etc., can be locked to the positioning templet through movement of the locking templet to a position in which the studs 20 are disposed within the slots 22. With the pattern elements locked to the positioned templet, it will be clear that they are secured in fixed relative positions and in such positions as to provide the pattern for forming the design on the work to be carved. In Figure 3, the pattern elements are shown locked to the positioning templet and ready 20 for application to a piece of work indicated at W. As previously mentioned the apparatus is designed and used in conjunction with relatively soft material such as wood or the like so that the pointed ends of the pin 17 can readily penetrate the work and thus hold the entire pattern in fixed position upon the work. In Figure 4 the pattern is shown applied to the work with the pins in penetrated position. After this operation the positioning templet can be removed from the pattern by manipulation of the locking templet, as will be understood, when the application of the sand blast to the work is then in order. In Figure 5 I 30 have shown the sand blasting instrument applied to the work, and it will be clear that the instrument is positioned to direct the blast of sand between the pattern elements so as to carve out of the work the wood around the pattern element and thereby form the design in the surface of the work.

During the sand blasting operation, the pattern is securely held against movement on the work by means of the pins 17 so that the carving of the work can be accurately and expeditiously carried on, and without requiring the skill in the manipulation of the instrument as is necessary with apparatus heretofore proposed.

55 As previously described, the pattern elements include a yieldable or compressible lamination 16, and in the applied position of the pattern to the work as shown in Figure 5 this lamination is disposed uppermost. By virtue of the fact that it is formed of yieldable or compressible material it is immune from the attack of the sand blast, and in its overlying relation with respect to the lower lamination 15, it will be clear 60 that it serves as a protector for the latter

to prevent the sand blast impinging on and wearing away the same.

After a piece of work has been carved as illustrated in Figure 1, the pattern can be removed from the work and the elements 70 thereof maintained in their proper relative positions by the application of the positioning templet thereto, the studs 20 being again projected into the slots 22 of the locking templet T' so that when the two templets 75 are lifted the pattern elements will be elevated from the work and securely held against movement one with relation to the other. It will thus be manifest that the pattern elements can be applied as a unit 80 to another piece of work for carving in the latter another design, and in this manner the pattern elements can be used indefinitely on various pieces of work.

Although I have herein shown and described only one form of apparatus for sand blast carving embodying my invention, it is to be understood that various changes and modifications may be made therein without departing from the spirit of the 90 invention and the spirit and scope of the appended claims.

I claim as my invention:

1. A pattern for sand blast carving comprising a laminated body having yieldable 95 or compressible material disposed uppermost when the pattern is in applied position to a piece of work:

2. A pattern for sand blast carving having positioning pins projecting from its lower side so as to be adapted to penetrate a piece of work when the pattern is applied thereto for removably securing the pattern in fixed position on the work.

3. A pattern for sand blast carving having pins extending therethrough so as to have portions projecting above and below the pattern.

4. An apparatus for sand blast carving comprising a plurality of pattern elements, means adapted to secure the elements to and against movement on a piece of work, and means by which the pattern elements can be removed from the work and maintained in fixed positions one with relation to the other to permit the application of the elements in the same positions to a second piece of work.

5. An apparatus for sand blast carving comprising a plurality of pattern elements, positioning pins projecting from the lower side of the elements for securing the elements to a piece of work in a manner to prevent movement of the elements on the work, and means by which the pattern elements can be removed from the work and maintained in fixed positions one with relation to the other to permit the application of the elements in the same positions to a second piece of work.

6. An apparatus for sand blast carving 130

- comprising a plurality of pattern elements, 5 positioning pins projecting from the lower side of the elements for securing the elements to a piece of work in a manner to prevent movement of the elements on the work, 10 positioning pins projecting from the upper side of the pattern elements, a positioning templet removably receiving the last mentioned pins in a manner to hold the pattern 15 elements in fixed relative positions, and means by which the pattern elements are detachably secured to the positioning templet.
7. An apparatus as embodied in claim 6 wherein the last means comprises members 20 on the pattern elements extending through the positioning templet, and a locking templet movable on the positioning templet to engage the members and secure the latter against removal from the positioning templet.
8. An apparatus for sand blast carving comprising a plurality of pattern elements, means adapted to secure the elements to and against movement on a piece of work, and 25 means by which the elements can be releasably locked and fixed in relative positions when removed from the work.
9. An apparatus for sand blast carving comprising a plurality of pattern elements, 30 positioning pins projecting from the lower side of the elements for securing the elements to a piece of work in a manner to prevent movement of the elements on the work, positioning pins projecting from the upper 35 side of the pattern elements, a positioning templet removably receiving the last mentioned pins in a manner to hold the pattern elements in fixed relative positions, a lock-
- ing templet on the positioning templet, co-acting means formed on the pattern elements 40 and locking templet for securing the elements to the positioning templet, and means by which the locking templet is secured to the positioning templet for movement to effect a release of said means to allow the removal of the pattern element from the positioning element.
10. An apparatus for sand blast carving comprising a plurality of pattern elements, 45 positioning pins projecting from the lower side of the elements for securing the elements to a piece of work in a manner to prevent movement of the elements on the work, positioning pins projecting from the upper 50 side of the pattern elements, a positioning templet removably receiving the last mentioned pins in a manner to hold the pattern 55 elements in fixed relative positions, a locking templet on the positioning templet studs 60 fixed to the pattern elements and extending through the locking and positioning templets and means for attaching the locking templet to the positioning templet to allow movement of the former to either of two extreme 65 positions, the studs being formed with shoulders and the locking templet with openings and slots in such manner that when the locking templet is in one extreme position the studs are disposed within the openings to allow the removal thereof from the locking templet and when in the other extreme position the studs are disposed within the slots 70 so that the walls of the slots engage the shoulders of the studs to lock the studs to the templet.

IRVING B. WELLINGTON.
